ASSIGNORS TO TRICO PRODUCTS CORPORATION, OF BUFFALO, NEW YORK

HORN CONSTRUCTION

Application filed November 17, 1930. Serial No. 496,309.

This invention relates to horns for giving warning notes or signals and particularly to such horns as are adapted for use on automobiles, boats or other vehicles.

5 The invention has particular reference to a signal horn in which a column of air is set into sound producing oscillation by a vibrating valve, and relates specifically to the design and structural relationships of various 10 parts comprising the sound generating and sound amplifying devices.

The horn includes a casing formed of a plurality of die castings, which may be rapidly produced at low cost, and which form a 15 housing for the sound generating mechanism and also a conduit or trumpet passage for directing and amplifying the sound waves that are produced within the sound box or housing by the sound generating mechanism.

20 The trumpet passage, defined by a pair of the casing forming die castings, is of spiral form, effecting compactness of the structure. The convolutions of the passage are spaced by single comparatively thin walls and 25 through which sound waves may be conducted for modifying and altering the original sound waves generated in the sound box before they are emitted from the mouth of the trumpet.

30 These and other objects and advantages will become apparent from the following description of typical devices embodying the principles of the invention, reference being made to the accompanying drawings, 35 wherein:—

Fig. 1 is a side elevational view of a horn constructed in accordance with the present invention;

Fig. 2 is a vertical cross-sectional view 40 taken on line 2—2 of Fig. 1;

Fig. 3 is a vertical cross-section in a plane normal to that of Fig. 2 and through the sound generating portion of the device;

Fig. 4 is a side elevation of a die-cast in- 45 sert portion of the sound amplifying means;

Fig. 5 is a substantially vertical sectional view taken through a modified horn; and

Fig. 6 is a vertical cross-sectional view 50 taken on line 6—6 of Fig. 5.

As shown in Fig. 1, the device consists of

a casing 10 which houses the sound producing mechanism and comprises the trumpet or sound augmenting and projecting means. The casing consists of a pair of complementary die-castings 11 and 12 each having a 55 continuous spiral trough 13 of substantially semi-circular cross-section, the diameters or widths of the spiral troughs increasing from the centers outwardly, and each convolution thereof being spaced from the adjacent convolution by a metal wall 14, also of spiral shape and of substantially uniform width. The members 11 and 12 are each extended and enlarged as indicated at 15 adjacent the outer trough ends and are adapted to be secured in such complementary relationship that the spiral troughs 13 merge to form a spiral passageway 15 of substantially circular cross-section, the diameter thereof increasing from the center of the castings outwardly. The 60 65 70 75 80 85 90 95 100

The inner face 17 of the casting 11 is preferably dished in order to provide for a substantially flat outer face 18 and the increasing depth of the convolute troughs 13. The central portion of the casting 12 is cupped outwardly at 19 to form a housing for sound producing mechanism. A block 21, having a spiral trough 22 terminating centrally in a reduced passage 23, is seated between the castings 11 and 12, the block closing the interior of the cupped portion 18 of the latter casting. The trough 22 complements the inner convolutions of the trough 13 in the casting 11 to form an inner continuation of the spiral passage 15, merging in a curve of comparatively large radius into the passage 23 which is substantially normal to the plane 90 of the outer face 18 of the casting 11.

A portion of the block 21 about the passage 23 is extended to provide an annular seat 25 for a valve 26. The latter has a hub 27 with a peripheral flange 28 thereabout, the flange being connected by coiled tension springs 29 disposed radially thereof to the casing or housing portion 19. A spider 31 having an annular seat 32 for bearing against medial portions of the springs 29 is adjustably re-

tained thereagainst by a set screw 33 and locking nut 34, the set screw having a conical tip seating in the central portion of the spider. A cap 35 is removably fitted over the 5 set screw and nut, preferably being threaded to the housing as shown in Fig. 2.

An exhaust or suction line 36 extending to the intake manifold of the vehicle engine or other source of less-than-atmospheric pressure 10 sure is attached at 37 to the casing portion 19, communicating with the interior thereof through a port or passage 38. A suitable valve (not shown) is preferably provided in the suction line to control the flow of fluid 15 therethrough for effecting operation of the horn. Air being drawn through the tube 36 will produce a condition of less-than-atmospheric pressure in the interior of the casing 19, causing air under atmospheric pressure in 20 the trumpet passage 15, 23 to force the valve 26 away from its seat 25 against the resistance of the springs 29. When a condition of atmospheric pressure again maintains within the chamber 19, due to passage of a stream 25 of air through the trumpet passage around the valve 26, the tension springs will return the valve to its seat. The sound waves created by such oscillatory movements of the valve or sound generating member toward 30 and away from its seat, which recur at highly frequent intervals, or by the pulses or vibrations set up in the air stream, or by both combined, are modified, amplified and directed by the trumpet passage.

35 The pitch or period of oscillation of the sound generating valve may be varied by adjusting the set screw 33, causing the spider 31, 32 which presses against the springs 29 to induce a different degree of tension therein.

40 In the modified construction shown in Figs. 5 and 6 the intermediate block 21 is omitted. The horn casing comprises die cast sections 40 and 41 each having a spiral trough 42 of semi-circular cross-section which increases in 45 radius from the center or inner convolution outward. These sections, held together by screws 43 complement each other to form a continuous convolute passage 44 terminating at the horn interior in a reduced neck 45 which is adapted to be alternately opened and closed by a sound generating valve 46. The valve is contained in a chamber 47 defined by the casing section 42, including an internally threaded tubular extension 48 thereon, and a 50 cup-shaped closure 49, threaded into the tubular extension 48. The latter carries radial springs 51 for supporting the valve, an adjustable set screw 52, and a fitting 53 for attaching the exhaust line 54. A spider 55 is 55 adjustably pressed against the springs 51 by the set screw 52.

A bell 56, preferably a single piece of metal stamped or spun to shape is pressed into an annular recess 57 formed in the outer end of 60 the spiral passage 44. The lower screw 43

preferably impinges the telescoped portion of the bell to positively retain it in the recess 57.

The operation of this horn is similar to that of Figs. 1 to 4 inclusive, the opening and closing movements of the valve, effected by suction maintaining in the line 54, inducing sound waves in the amplifying trumpet passage 44, 56. The pitch of the signal note may be varied by adjustment of the set screw 52, and the valve 46 may be adjusted relative to its seat by turning the threaded closure 49 by which the springs 51 are carried. The closure may also be turned to vary the tension in the springs 51 and may be locked in adjusted position by a set screw 58, threaded into the tubular casing portion 48.

It will now be understood that the present invention provides a compact horn structure, the long effective trumpet passage being coiled into a relatively small spiral and formed of two disc-like die-castings which may be economically and rapidly produced. The sound gathering mechanism, similar to that disclosed in co-pending application Serial No. 486,288, filed Oct. 3, 1930, may, as shown in Fig. 6, be provided with a plurality of adjustments for effecting changes in the tension of the valve actuating springs. The tone quality of the device is attributable partially to the shape of the trumpet passage and partially to the manner of formation of the passage, the passage convolutions being spaced by single and comparatively thin walls which may transmit sound waves or vibrations to modify the characteristics of the resulting sound waves.

It will be further understood that the specific devices described may be modified in various details, and it is intended that the invention should be commensurate with the scope of the following claims.

What is claimed is:

1. A horn casing, comprising a pair of complementary sections, each of said sections having a spiral trough therein increasing in depth from one to the other end of the spiral, said spiral troughs together forming a spiral trumpet passage of cross section increasing from one to the other end thereof, one of said sections having a chamber formed integrally therewith for containing sound generating mechanism, and a passage opening between said chamber and the smaller end of said spiral passage.

2. A horn comprising a casing having a spiral trumpet passage and a sound chamber, a connecting passage extending between the inner convolution of said spiral passage and said sound box, said connecting passage extending in a plane substantially normal to said spiral, a sound generating element in said chamber adapted to alternately seat and unseat over said passage for inducing sound waves in said passages.

3. A horn comprising a pair of complementary casing sections, the first of said casings having a spiral trough extending from the center thereof outwardly, the second of said sections having an opposed spiral trough complementing the outer convolutions of said first trough to form an outer spiral passage, said sound section having a recessed chamber for receiving sound generating mechanism including a movable valve, a filler section disposed between said first and second sections and substantially closing said recessed chamber, said filler section having a spiral trough complementing the inner convolutions of said first section to form an inner spiral passage communicating with said outer spiral passage, said filler section having a connecting passage merging into the inner end of said inner spiral passage and opening into said chamber, and said connecting passage being adapted to be alternately covered and uncovered by said movable valve.
4. A horn comprising a pair of complementary casing sections, the first thereof having a spiral trough extending from the center outwardly, the second thereof having a complementary spiral trough extending from a medial portion of said first-mentioned spiral outwardly, a recessed chamber formed in said second section, and a filler section substantially closing said chamber and disposed between said first and second sections, said filler section having a spiral trough terminating centrally thereof in a connecting passage opening into said chamber, the trough of said first section cooperating with the troughs of said second section and said filler section to form a continuous spiral passage from said connecting passage outwardly.
5. A horn comprising a pair of casing sections, each having a spiral trough extending from the center thereof outwardly, said troughs complementing each other to form a spiral passage of increasing cross section from the center outwardly, one of said sections having a chamber forming an extension and a passage opening into said chamber and merging into the inner end of said spiral passage.
6. A horn including a pair of casing sections each having a trough formed therein, said troughs complementing each other to form a trumpet passage, said sections being secured together by threaded fasteners extending therethrough, and a bell telescoped into one end of said passage and removably retained therein by engagement with one of said threaded fasteners.
7. A horn comprising a casing section having a sound chamber and passage opening outwardly therefrom, said chamber being threaded internally thereof, and a closure threaded into said chamber, a sound generating member supported in said chamber by springs attached to said closure, said mem-
- ber being adapted to alternately cover and uncover said passage, and said closure being effective upon turning thereof to support said member varying distances from said passage and to vary the tension of said springs.
8. A suction operated horn comprising a casing having a tubular portion threaded internally thereof, and a passage substantially coaxially of said tubular portion, a closure threaded into said tubular portion, a sound generating member for alternately covering and uncovering said passage, radial springs extending between said closure and said sound generating member for supporting the latter, and an annular member adjustable relative to said closure for bearing against and varying the tension of said radial springs, said closure being adjustable by turning relative to said casing to vary the tension in said springs and to vary the normal spring pressure holding said sound generating member in position covering said passage.
